BAG STRUCTURE

Thomas E. Piazze, Milwaukee, Wis., assignor, by
mesne assignments, to Marshall & Ilsley Bank,
Milwaukee, Wis., a Wisconsin bank

Application April 1, 1938, Serial No. 199,369

1 Claim. (Cl. 229—53)

My present invention relates generally to improvements in the art of manufacturing receptacles for confining batches of various commodities, and relates more specifically to improvements in the construction of bags formed of cellulose film or similar relatively thin and frail sheet material.

In general, an object of my present invention is to provide an improved bag structure formed of cellulose film or the like, which can be more readily distended, loaded and closed and sealed without danger of tearing.

It is common commercial practice in the art of handling and merchandising many granular commodities, to provide transparent bags formed of cellulose film or other thin and relatively transparent sheet material, for the reception and concealment of batches of the granular material. These bags are ordinarily formed from a continuous ribbon of stock which is folded and glued into tubular formation and severed into successive sections each of which is subsequently transversely folded and fastened at one end so as to produce a flattened bag. These bags are subsequently stacked in flattened condition upon each other and distributed to the users in bundles, thus sharply creasing the longitudinally folded side edges of the bag structures especially adjacent to the open end of each bag. When the bags are to be filled, each bag is distended by hand for admission of the batch of commodity, and because of the thin and relatively frail character of the cellulose film, and the tension applied to the edges of the bag bounding the opening, these prior bag structures frequently tear inwardly from these edges and become useless. When a tear once starts, it will rapidly continue into the body of the bag and will make the same useless as a container. After each bag has been supplied with commodity, the open end is first pressed into flat condition and is subsequently transversely folded and refolded by hand to produce a double overlapped seal which is finally stapled or otherwise fastened to maintain the closure. Because of the fact that cellulose film has no marked grain which will cause it to fold along a definite and straight line, the present method of closing these bags relies entirely upon the accuracy in performance of the operator in order to produce a straight and uniform fold, and hence a neat seal. The result is, that very few of the hand closed bags of this type, are neatly sealed with folds of uniform width, and the appearance of the successive packages is not at all uniform but in fact very irregular.

It is therefore a more specific object of my present invention to provide extremely simple yet highly effective instrumentalities for obviating such undesirable tearing of bags formed of cellulose film or the like, and for producing neat and uniform folded closures after the bags have been supplied with commodity.

In accordance with my present invention, these improved results are obtained by merely transversely scoring each bag transversely of its length at the place where it is desired to produce the first final closing or sealing fold. It has been found that this transverse scoring not only permits more convenient and uniform folding of the bag during closure along an absolutely definite line located a definite distance from the extreme bag end, to thereby provide neat and uniform closing folds; but the scoring also relieves the edge tension during distending of the bag and thus reduces danger of tearing, and furthermore retards any tearing which takes place starting at the free edge of the bag, from proceeding beyond the score lines, thus eliminating excessive waste of bags.

25 A clear conception of an embodiment of my present invention, and of the mode of constructing and of utilizing bags manufactured in accordance with the improvement, may be had by referring to the drawing accompanying and forming a part of this specification wherein like reference characters designate the same or similar parts in the various views.

Fig. 1 is a fragmentary perspective view showing the distended open end of one type of the improved bags;

Fig. 2 is a plan view of one of the improved bags of Fig. 1 in collapsed condition, portions of the top of the bag having been broken away;

Fig. 3 is a fragmentary plan view of the top of the bag of Fig. 1, after the first closing fold has been made;

Fig. 4 is a similar fragmentary view, showing the bag opening finally sealed by double folding and stapling;

45 Fig. 5 is a section through the open bag end, taken along the line 5—5 of Fig. 2 and showing the body of the bag slightly distended;

Fig. 6 is a similar section through the inlet end of the bag, the section having been taken along the line 6—6 of Fig. 3;

Fig. 7 is another similar section through the inlet end of the finally sealed bag, the section being taken along the line 7—7 of Fig. 4; and

55 Fig. 8 is a plan view of a modified type of bag embodying my invention.

While I have shown the invention as being applied to an accordion type of bag formed of transparent cellulose film and finally sealed by stapling, it is not the intent to thereby unnecessarily restrict the scope, since the improvement is more generally applicable to other types of bags formed of other kinds of sheet material and finally sealed by other methods.

Referring to the drawing, the transparent bags illustrated therein are preferably formed of a sheet of cellulose film or the like folded to provide a smooth front wall 10; an overlapped and adhesively joined rear wall 11; intervening relatively and inwardly foldable side walls 12 connected to the front and rear walls 10, 11 along sharp outer edge creases 13, and to each other along similar inner edge creases 14; and a bottom flap 15 folded over and secured to either the front or the rear wall by means of adhesive or otherwise so as to complete the bag assemblage. The walls 10, 11, 12 may be of various lengths and widths depending upon the desired shape and holding capacity, and the open end of the bag assemblage may be provided with straight alined edges 16 at the outermost ends of the rear and side walls 11, 12, and with a cut-out forming a depressed end edge 17 on the front wall 10, this depression serving to permit more convenient opening of the mouth of the bag from collapsed condition. While the edges 16, 17 are shown as being substantially straight or rectilinear, they may be serrated or curved, these various formations being well known to those skilled in the art.

The bag assemblage just described is of well known construction, and in accordance with my present invention, I provide scoring 18, 19, 20 transversely across the walls 10, 11, 12 respectively, so that when the open bag end is collapsed, all of the score lines will be brought into juxtaposition. The adjoining scorings 18, 19, 20 will then permit simultaneous and uniform folding of the corresponding end portions of all of the panels or walls 10, 11, 12 in the form of a common flap 21, and the scoring 18, 19, 20 should preferably be carried completely across the creases 13, 14 in order to produce the best results.

In the type of bag shown in Figs. 1 to 7 inclusive, the portions of the panels 10, 11, 12 between the edges 16, 17 and the transverse score lines 18, 19, 20, have parallel edges disposed in alinement with the creases 13, 14, as illustrated in Fig. 2, but in Fig. 8 I have shown a modified type of bag wherein the mouth of the bag between the edges 16, 17' and the scoring, has been stretched in any suitable manner so as to somewhat enlarge or elongate the edges 16', 17' beyond the lineal length of the score lines. It has been found, that during distension of a bag having no transverse scoring near its open end, the extreme bag edges 16, 17 are subjected to considerable tension and frequently tear either along the side creases or at points between these creases. The scorings 18, 19, 20 definitely relieve this edge tension at the free edges and throw the strain upon the bag at the score lines. In a bag of the type shown in Figs. 1 and 2, the portions of the panels above the scoring assume a curvature and draw inwardly as illustrated in Fig. 1, and while the scoring in this type of bag still effectively protects the free edge and prevents excessive tearing, the inward movement of these edges tends to somewhat obstruct the introduction of the material. In a bag formed as shown in Fig. 8, the previous stretching of the

5 mouth may be made sufficient to approximately compensate for the inward movement of the edges 16', 17' during distension of the assemblage, so that the bag opening remains the same 10 as the transverse area of the main body of the distended bag, while the edges 16', 17' are still relieved from undesirable tension and resultant tearing. This is an extremely important feature 15 of my present invention, especially as applied to bags formed of cellulose film or similar material.

When the bag assemblages have been thus formed and scored, they may be stacked for handling, storage and shipment, and are also 15 ready for use. In order to supply each bag with commodity, it is first necessary to distend the opening as shown in Fig. 1, and while the scoring 18, 19, 20 does not impede this opening operation, it has been found that the score lines 20 besides relieving the mouth edges from excessive tension, also retard the walls 10, 11, 12 from tearing beyond the score lines when a slight tear is accidentally started at one of the free edges 16, 17. This retardation or obstruction to 25 continuation of the tears is especially noticeable at the creases 13, 14 since the crossing or intersection of the scorings 18, 19, 20 at these creases provides a slight kink in the material which is 30 obstructive to the tearing action.

35 After the bag has been distended and the commodity has been introduced, the open bag end should first be collapsed as depicted in Fig. 5, and the flap 21 should be subsequently folded downwardly along the scorings 18, 19, 20 as shown in Figs. 3 and 6. If a single fold closure is sufficient, the flap 21 may be secured in folded position with adhesive or by stapling, but ordinarily a double fold closure is more desirable. The initially folded flap 21, may then be again folded 40 against either the front or rear wall 10, 11 as illustrated in Figs. 4 and 7, after which staples 22 or other fastening means may be applied to complete the closure. The hinge joint afforded by the scorings 18, 19, 20 will obviously effect 45 convenient and uniform folding of the end flaps 21 on the successive bags, and the free edges of these flaps will insure uniform subsequent folding, thereby insuring neat and absolutely uniform closures which can also be quickly produced without relying solely upon the judgment and accuracy of the individual performing the closing operation.

50 From the foregoing detailed description it will be apparent that while my invention merely comprises the provision of the transverse alined scorings 18, 19, 20, it effectively accomplishes the two-fold object of preventing excessive tearing of the bag at the mouth during opening and filling, due to the action of the score lines, as well as facilitating the production of uniform closure folds. While these transverse scorings 55 will not positively prevent destruction of bags by tearing, they do materially relieve the edge tension and thus reduce the danger of tearing to a minimum. The retardation to continued tearing produced by the score lines, also makes it possible to use such bags which may have been slightly worn at the mouth during initial opening. Because all of the scorings 18, 19, 20 are 60 located the same distance from the extreme end of the bag, and lie in the same transverse plane, they will assume adjoining positions when the bag is collapsed so as to insure uniform folding, and these score lines may obviously be simultaneously produced with a single simple creas- 65 70 75

ing operation. The invention has proven extremely advantageous in actual commercial use, and may be applied to various types and sizes of bags.

It should be understood that it is not desired to limit the invention to the exact details of construction or to the precise mode of use, herein shown and described, for various modifications within the scope of the claim may occur to persons skilled in the art.

I claim:

A bag of thin highly flexible cellulose sheet material adapted to be collapsed into flat condition and susceptible of contracting at the bag mouth when the bag is distended, said bag including a closed bottom and having a score line disposed completely thereabout adjacent to and spaced from and substantially parallel to the mouth edge, said bag when in collapsed flat con-

dition having the opposite outer marginal edges of its mouth portion above said score line flaring outwardly at an angle from the score line to permanently enlarge and gradually expand said mouth portion, the body of said bag when in said collapsed flat condition below said score line having marginal edges defining a substantially rectangular configuration, said score line serving to arrest tearing of the cellulose bag material at the mouth portion during filling and said outwardly flaring mouth portion serving to compensate for normal contraction of the mouth portion when the bag is distended for filling, to the end that when so distended the entire configuration of the bag including the mouth portion above the score line is substantially rectangular.
